Attest:

UNITED STATES PATENT OFFICE.

AMOS O. COLE, OF KANKAKEE, ILLINOIS.

GAME-REGISTER.

SPECIFICATION forming part of Letters Patent No. 550,123, dated November 19, 1895.

Application filed February 11, 1895. Serial No. 537,941. (No model.)

To all whom it may concern:

Be it known that I, AMOS O. COLE, a citizen of the United States, residing at Kankakee, in the county of Kankakee and State of Illinois, have invented certain new and useful Improvements in Game-Counters; and I do hereby declare the following to be a full, clear, and exact description of the invention, such as will enable others skilled in the art to 50 which it appertains to make and use the same.

This invention relates to an improved device for scoring games and more especially with reference to games of cards, and has for its object to provide a simple and convenient arrangement of this character, as will be hereinafter set forth.

In the drawings, Figure 1 is a plan; Fig. 2, a plan of the interior, the cover of the same being removed; Fig. 3, a transverse section 20 on line 3, Fig. 2, looking in the direction indicated by the arrow; Fig. 4, a transverse section on angular line 4, Fig. 2; and Fig. 5 a broken-away view in perspective of the dial-wheels, showing the operating features in detail.

A may represent a case or box of any suitable form, having a removable cover or top B. The top of the cover is provided with a units dial-face C and a dial-face C', having 30 numerals disposed thereon in a circle. The lower end of a spindle a is provided with a suitable bearing in the bottom of the inclosing case, as at a', the upper end projecting through the cover and having an indicating-hand a², rigidly mounted thereon. This hand is provided with a finger-grasp a³, so that the same may be conveniently rotated together with its spindle. A units dial-wheel D is rigidly mounted on spindle a and is provided 35 at one side with a turned-up lip a⁴ and a laterally-projecting tooth a⁵. A multiplying dial-wheel D' is rigidly mounted on a spindle b, provided with suitable bearings in the top and bottom of the case and having an indicating-hand secured to the upper projecting end. The wheel D' is provided at intervals 45 with a series of teeth d, corresponding in number to the divisions on the dial-face.

One end of a spring-pawl d' is secured to 50 the interior side wall of the case, as at d², the opposite loose end extending across the joining edges of the dial-wheels, as shown. This

pawl is bent downwardly, so as to have frictional contact with the upper side of the multiplying-wheel, the extreme disengaged end 55 being bent upwardly, as at d³, so that the lip on the units-wheel will readily clear the same when being rotated in either direction. The loose end of the pawl is provided with a notch 60 for the engagement of the teeth of the multiplying-wheel.

The units-wheel is numbered from "1" to "10" and the multiplying-wheel from "1" to "12," which arrangement is more especially adapted for keeping the count in the game of 65 whist. This arrangement or disposition of the numerals or other characters on the dial-wheels may, however, be varied as circumstances may require.

The teeth on the multiplying-wheel correspond in number with the divisions on its dial-face.

In operation, with each complete revolution of the units-wheel the lip a⁴ thereon passes underneath the loose end of the pawl and 70 raises the same up out of engagement with the engaged tooth of the multiplying-wheel at the same time the tooth a⁵ on the units-wheel comes in contact with the same tooth that the pawl has just been disengaged from 75 and rotates the multiplying-wheel the distance of one division—that is, with each complete revolution of the units-wheel the multiplying-wheel registers "10," aggregating one hundred and twenty when the units-wheel 80 shall have made twelve complete revolutions. By this arrangement the points of any game 85 may be scored up to one hundred and twenty, games of ten points or less being counted on the units-wheel.

Having thus described my invention, what I claim as new, and desire to secure by Letters Patent, is—

1. In a device of the kind described, the combination with an inclosing case, having 95 indicating dial-faces on the top side thereof, a spindle, journaled in said case, the upper end projecting through the top, an indicating-hand, secured to the projecting end of said spindle, a units-wheel, rigidly mounted 100 on said spindle and provided with an upturned lip and a projecting tooth, a companion spindle, an indicating-hand, secured to the upper end thereof, a multiplying-wheel,

rigidly mounted on said companion spindle and provided with teeth disposed at intervals, and a spring-pawl, rigidly secured at one end, the loose end extending across and bent 5 downwardly to normally engage with the teeth of the multiplying-wheel, substantially as described.

2. In a device of the kind described, the combination with an inclosing case, of a spindle, a units-wheel, provided with an upturned lip and a projecting tooth and rigidly mounted on said spindle, a companion spindle, a multiplying-wheel, provided with a number of teeth disposed at intervals and rigidly mount-

ed on said companion spindle, and a spring-pawl, adapted to detachably engage with said teeth, whereby with each complete revolution of the units-wheel the pawl is raised out of engagement and the multiplying-wheel moved the space of one division, substantially as de- 15 scribed. 20

In testimony whereof I affix my signature in presence of two witnesses.

AMOS O. COLE.
